UNITED STATES PATENT OFFICE

FREDERICK WILLIAM AUSTIN, OF OLDHAM, ENGLAND.

LOOM FOR WEAVING TUFTED PILE FABRICS AND APPARATUS FOR USE THEREWITH.

Application filed May 15, 1925, Serial No. 30,643, and in Great Britain May 17, 1924.

In looms for weaving tufted pile fabrics in which grippers or devices are provided for drawing off portions of tuft yarn from spools, and, after the portions drawn off are severed 5 from the yarns on the spools, inserting them between warp threads, use has been made or proposed of transferring mechanisms which disengage tube frames holding spools and placed two or more in line end to end to 10 present practically continuous lines of spools and tubes from carrying chains and move them in line into a position in which they present tuft yarn to the grippers or devices for drawing off portions to be severed and 15 after the severance thereof move the tube frames from that position back again into engagement with the carrying chains while the grippers insert the severed portions of tuft yarn between warp threads.

20 This invention of improvements in looms for weaving tufted pile fabrics relates to the mechanism for disengaging and removing tube frames with guide tubes for the tuft yarn and spools of tuft yarn from the carrying chains used to convey the tube frames and spools of tuft yarn in due order to and from places at which they are required to be used for the supply of the tuft yarn for insertion between warp threads, for causing the 25 tube frames to insert tuft yarn between warp threads and afterwards for restoring the tube frames to the carrying chains.

20 The invention consists in mechanism for disengaging and removing the tube frames 30 from the carrying chains and causing them to insert tuft yarn between warp threads which, retaining the advantage hitherto obtained only in looms in which tube frames are used singly, that the tube frames after removal from the carrying chains are themselves made to insert tuft yarn between warp threads, to draw off tuft yarn from the spools, to be withdrawn to a position at a predetermined distance from the warp 35 threads in order to leave tuft yarn between the warp threads and to draw off tuft yarn from the spools, and to remain in that position in order to hold taut the portions drawn off until after the severance of the portions 40 of tuft yarn between warp threads from the yarn on the spools, and are then restored to the carrying chains, presents in comparison with mechanism hitherto provided for the like purpose, the advantages that it enables looms to be built for weaving fabrics of 45 greater width and of any width requisite without the use of inconveniently long and heavy tube frames and spools for holding tuft yarn and enables looms to be built of parts in sets each member of which is interchangeable with or corresponds closely to the corresponding member of another set so that any suitable number of sets or parts can be used with other necessary co-operating parts in building looms of any width desirable with any number of tube frames operated and used simultaneously and in alignment and that similar tube frames can be used in any of such looms. A further advantage afforded by the mechanism provided 50 according to this invention for removing tube frames from carrying chains, causing the tube frames to insert tuft yarn between warp threads and afterwards restoring the tube frames to the carrying chains, is that the tube frames operated and used two or more simultaneously and in alignment are held immovably and irremovably in the parts holding and operating them and being held securely can be operated speedily.

55 According to this invention, holders to be hereinafter further described and illustrated by the accompanying drawings, are provided one on each side and one, two or more in a position or positions intermediate between the sides of a tufted pile fabric loom which present notches to receive hook like projections extending in the general plane of end plates of tube frames and are adapted to receive tube frames applied end to end in line and presenting practically continuous lines of spools and tubes and are oscillatably mounted upon parts provided for moving them up and down and are in connection with means for oscillating them and are provided with pressing devices oscillatably mounted upon them and in connection with means for oscillating such devices for pressing upon and releasing the tails of pivoted hooks of tube frames and releasing such tube frames from carrying chains and holding them in and releasing them from the holders, so that the holders are capable of taking tube frames in line end to end from carrying chains and, while continuing to hold them in line end to end, inserting the yarn tubes of the tube frames between the warp threads in the loom, being drawn back to leave portions of tuft yarn between the warp threads and to cause other portions of requisite 60 length to be drawn from the spools and out through the tubes to be left to protrude

therethrough and, after portions of tuft yarn between warp threads have been severed from yarn on the spools, restoring the tube frames again to the carrying chains and making it possible to apply in the use of tube frames in line end to end the method hitherto only applied in looms in which tube frames are used singly.

Figs. 1 and 2 of the accompanying drawings show an illustrative example of the mechanism according to this invention for disengaging tube frames from the carrying chains and inserting tuft yarns between warp threads and again restoring the tube frames to the carrying chains in a loom, and other mechanism used in a loom, sufficiently to illustrate this invention and to make clear the manner of carrying it into effect. The framework is omitted for simplicity, and for clearness some parts shown in Fig. 2 are omitted from Fig. 1.

Fig. 1 is a side elevation partly in vertical section and Fig. 2 is a front elevation drawn in two parts on two sheets. Fig. 3 is a front elevation and Fig. 4 a side elevation of a tube frame of a form adapted for use with the mechanism illustrated by Figs. 1 and 2, and Fig. 5 is a plan of parts shown in Figs. 3 and 4. Fig. 6 is a front elevation and Fig. 7 a plan of a holder at the left hand of a loom and Fig. 8 is a side elevation thereof. Fig. 9 is a front elevation and Fig. 10 is a plan of a holder intermediate between the sides of the loom and Fig. 11 is a side elevation thereof. Fig. 12 is a front elevation and Fig. 13 is a plan of a holder at the right hand side of the loom. Fig. 14 is a perspective view of a holder at the right hand side of the loom and Fig. 15 is a perspective view of a holder intermediate between the sides of the loom. The same numerals of reference indicate corresponding parts in different figures.

In the mechanism shown in Figs. 1 and 2, 45 1, 2 are holders of two forms for engagement with the tube frames 3 with yarn tubes 4 and carrying spools 5, one of which tube frames 3 with its yarn tubes 4 and spool 5 is shown more clearly in Figs. 3 and 4, and 50 for removing such tube frames 3 from the carrying chains 6 and presenting them in line end to end and causing them to insert their tubes 4 and so tuft yarn, between warp threads and after the severance of the inserted tufts restoring the tube frames 3 to the carrying chains 6.

Apart from being furnished with bearing rollers 61 for travelling on supports the carrying chains 6 are of known form. The 60 number of chains 6 provided depends upon the number of tube frames 3 to be used in line end to end and consequently is always greater by one than the number of tube frames 3 so to be used. The warp threads 65 and the weft are omitted from the drawing

for clearness but their position is indicated sufficiently by the healds 7, the slay 8, the reed 9, the supporting plate 10 and the knives 11, 12 which are similar and worked similarly to those used in looms of already 70 well known construction but are made of a width corresponding to the width of the fabric to be produced in a loom. The tube frames 3 and the end plates 18 provided therein form no part of the present invention but are represented in the accompanying drawings and will be briefly described herein to facilitate description of the mechanism of the loom. The end plates 18 form the subject of application for United States 80 Letters Patent No. 30,644 dated May 15th, 1925. Each end plate 18 is formed mainly as a plate presenting a plane outer surface directed outwardly from a spool in the tube frame on which it is provided and presents 85 a projection 43 in its general plane to enter between the side plates of a link of a carrying chain and also presents a hook like projection 19 extending in its general plane downwardly and to the rear when the end 90 plate 18 is to be disengaged from a chain 6. The projection 19 is shown as narrowing towards its end. Each end plate 18 has a hook 20 capable of projection and retraction laterally and furnished with a projection or 95 tail 21 extending laterally within the length of the tube frame by which the hook 20 may be retracted and disengaged from the chain 6.

Each end plate 18 is formed on the side 100 to be turned towards a spool 5 in the tube frame with projections 44, 45 extending laterally for the attachment of a bar 46 furnished with yarn tubes to be at the rear and bottom when the end plate 18 is in position for disengagement from a carrying chain 6. The holders 1, 2 are mounted by means of pivots 13, 14 respectively on arms 15, 16 of two forms carried by and movable by a shaft 17 mounted to be oscillated by 105 means of a cam and spring in a suitable framework, which cam and spring and framework are not shown but are similar to corresponding parts in looms already well known, into a top position for the holders 110 1, 2 to receive tube frames 3 from the carrying chains 6, then into a bottom position for the tuft yarns to be inserted between warp threads, then into a lower intermediate position for tuft yarn to be drawn from spools 115 5 in the tube frames 3 by the movement of the tube frames 3 from the lower position to that intermediate position and for the tuft yarn inserted between the warp threads to be cut off from that on the spools 5, then 120 again to the top position to restore tube frames 3 to the carrying chains 6 and lastly into an upper intermediate position to allow the tube frames 3 released to be moved from 125 above the holders 1, 2 and others to be 129

brought above them to be engaged thereby.

The arm 15 for carrying a holder 1 is formed in two parts fastened together as by bolts namely a part 151 forked for the 5 holder 1 to be mounted between the jaws forming the fork and a part 152 fast on the shaft 17.

The arms 15 at the two sides of the loom are similar but have their parts and in particular, the forked parts 151 disposed 10 reversely as regards lateral direction so as to be of opposite hand and apart from the formation of the forked part 151 and corresponding forked part at the other side of 15 the loom these two arms are similar to corresponding arms employed in looms for weaving pile fabrics by means of single tube frames extending across the width of the fabrics being woven. Similarly an arm 16 20 intermediate between the sides of the loom is formed in two parts fastened together as by bolts namely a part 161 forked to receive the holder 2 and a part 162 fast on the shaft 17.

25 The number of these arms 15, 16 with forked parts 151 and 161 provided in a loom is greater by one than the number of tube frames 3 to be taken from and restored to the carrying chains 6 at one time and 30 consequently in any case there is one less arm 16 than there are tube frames 3 to be taken at one time.

Each forked part 151 supports a holder 1 and the one or each forked part 161 provided in a loom supports a holder 2. The 35 two holders 1 are of opposite hand as indicated at the two sides of Fig. 2. There may be one holder 2 or more according as two or more tube frames 3 are to be taken from 40 and restored to the carrying chains 6 at one time. When two or more holders 2 are provided they are made alike. Fig. 2 shows two holders 2.

Each holder 1 or 2 comprises a plate connected by the pivot 13 to the forked part 151 or 161 of the arm 15 or 16 carrying it and presents a notch 22 narrowing downwards to receive downwardly extending hooks 19 of the end plates 18 of tube frames 50 3, and a downwardly extending projection 23, affording bearing for the lower angles of end plates.

Each holder 2 to be applied in intermediate positions between the sides of a 55 loom is adapted to receive two end plates 18 at a time by being provided with a notch 22 and a projection 23 of sufficient width in the direction across the loom to receive the hooks 19 and lower angles of 60 two end plates 18 applied one against the other. The holders are each adapted to receive one end plate 18 being provided with a notch 22 to receive the hook 19 and a projection 23 to afford bearing for the lower angle of one end plate 18 and being

provided with a curved or inclined face 26 directed inwardly across the loom to press together the tube frames 3 placed end to end.

To each holder 1 or 2 there is pivoted 70 an arm 27 with two projections 28 in the case of a holder 2 in an intermediate position between the sides of a loom or with one projection 28 in the case of a holder 1 at the side of a loom to engage with the 75 hooks or hook 20 provided on the end plates or end plate 18 in connection with a chain 6 to which the holder 2 or 1 may be presented and thereby to disengage the hooks or hook 20 from the chain 6 and also to 80 hold the end plates or end plate 18 firmly in the notches 22 of the holders 2 or 1, by bearing on the tails of the hooks 20 and on the upper parts of the hooks 19.

Connecting rods 29 adjustable in length 85 and surrounding the pivots of the arms 27 connect the holders 1 and 2 to studs in the arms 30 fast on a shaft 31 mounted in bearings in brackets 32 carried by the arms 15, 16. A stud 33 in an arm 34 fast on the 90 shaft 31 is connected by a connecting rod 35 to a stud 36 in a lever 37 mounted loose upon the shaft 17 and a connecting rod 38 moved by a stationary cam or other device.

Studs in the arms 27 are connected by 95 connecting rods 39 adjustable in length to studs in arms 40 fast upon a shaft 41 which is also mounted in bearings in the brackets 32 and moved by means of a moving or stationary cam or other device.

100 The movements to be given to the holders 1 and 2 and the arms 27 by means of the shafts 17, 31 and 41 are precisely similar to the movements given by means of corresponding shafts to the holders and tube frames releasing and gripping arms used in looms already well known for inserting tuft yarn in pile fabrics of the width corresponding to the length of a single spool

110 of tuft yarn and consequently the movements of the shafts 17, 31 and 41 are effected by mechanism similar to that used for operating the corresponding shafts of such looms and so not needing description herein. The shaft 17 being moved at appropriate 115 times in the working of the loom to raise and lower the holders 1, 2, the holders 1, 2, are presented to tube plates carried by the chain 6 and lowered into position for the tubes 4 of tube frames in the holders 1, 2 to pass between warp threads and to remain in that position for a suitable time and then raised into the position in which they are indicated in Figs. 1 and 2 to withdraw

120 the tubes 4 from between warp threads and to draw portions of tuft yarn from the spools 5 and to leave space between the tubes 4 and the warp threads for the passage of the knives 11, 12 and then after the 125 action of the knives 11, 12 are raised to re-

130

turn tube frames to the chains 6 then lowered to allow other tube frames 3 to be brought into position to be engaged by the holders 1, 2 and then raised again to engage these other tube frames 3. By the movement of the connecting rods 29 connected with the holders 1 and 2 and the shaft 31 the holders 1, 2 are moved at appropriate times so that the holders 1, 2 receive tube frames 3 from the chains 6, present the tubes 4 of the tube frames 3 obliquely to and introduce them between the warp threads and turn them into position to place the tuft yarns extending through them in a vertical or approximately vertical position and after the portions of tuft yarns inserted between warp threads have been cut off from the yarn on the spools 5, the holders 1, 2 present the tube frames 3 in position to be engaged with the chains 6. By the movement of the connecting rods 39 connected with the shaft 41 and the arms 27 mounted on the holders 1, 2, the projections 28 are made to engage with the hooks 20 for disengaging them from the chains 6 and for pressing on the hooks 20 and the hooks 19 and keeping the tube frames 3 held in the holders 1, 2 and when the holders 1, 2 present the tube frames 3 again to the chains 6 to relieve the hooks 20 from pressure so that the springs 48 used therewith may reengage the hooks 20 with the chains 6.

When the holders 1, 2 are presented to tube frames 3 on the chains 6 the downwardly projecting hooks 19 of the end frames 18 are received in the notches 22 of the holders 1, 2 and the lower angles of the end plates 18 bear on the projections 23 so that secure and precise bearing of the tube frames 3 in the holders 1, 2 is brought about and when the arms 27 are made to press on the tails 21 of the hooks 20 to disengage them from the chains 6 they will continue to press on the tails 21 and on the hooks 19 of the end plates 18 and so will hold the tube frames 3 firmly and immovably in the holders 1, 2 and against accidental or other removal therefrom during movement from the chain 6 to the warp threads, during movement while the tubes are between warp threads, during movement into position for tuft yarn inserted between warp threads to be drawn off from the spools, and for the portions between warp threads to be cut off from yarn on the spools 5 and during the return movement of the tube frames 3 back to the chains 6. Further when the holder 1 and the corresponding holder at the other side of the loom are presented to the end plates 18 of tube frames 3 contact of the end plates 18 with the curved or inclined face 26 and the corresponding face at the other side of the loom will cause the tube frames 3 which are placed in line to be pressed together end

to end in the line across the loom so that being so pressed together and held firmly in the holders by the arms 27 the line of tube frames 3 applied end to end will act as though it were one tube frame extending from side to side of the loom. Obviously any number of parts shown as mounted upon and operated by means of the shafts 17, 31, 41 for holding and working tube frames 3 may be provided in order to provide for the holding and working of any number of tube frames 3 end to end in line with spools 5 in them which it may be requisite to provide for in the construction of a loom.

The mechanism employed according to this invention may be different in detail in different cases. For example, instead of forked arms to carry the holders for tube frames, arms with pivots projecting on one side or both sides may be used and the projections or parts for engaging with the tails of the hooks on end plates may be made to work up and down or horizontally or otherwise according to the formation and disposition of the hooks and the tube frames to be employed may be provided with end plates of appropriate form or construction and the holders to receive the tube frames may be formed in any way requisite to correspond with them.

What I do claim as my invention and desire to secure by Letters Patent is:—

1. In a mechanism for taking tube frames carrying spools of tuft yarn from carrying chains and presenting the yarn tubes of such tube frames between warp threads in a tufted pile fabric loom and after severance of the tuft yarn between the warp threads from that remaining on the spools, restoring the tube frames to the carrying chains, an intermediate holder intermediate between the sides of the loom which presenting a notch for receiving hook like projections extending in the general plane of end plates of tube frames is adapted to receive simultaneously two end plates of tube frames placed end to end in line, pressing means mounted to be oscillated on said intermediate holder for acting upon and releasing chain engaging devices on tube frame end plates in the notch of said holder and holding tube frame end plates therein, two other holders at opposite sides of the loom each of which other holders presenting a notch for receiving hook like projections extending in the general plane of end plates of tube frames is adapted to receive one tube frame end plate at a time, pressing means respectively mounted to be oscillated on said other holders for acting upon and releasing chain engaging devices on tube frame end plates in the notches of said other holders and holding tube frame end plates therein, intermediate carrying means intermediate be

tween the sides of the loom providing pivotal attachment for said intermediate holder, lateral carrying means at the sides of the loom providing pivotal attachment for said other holders, means for moving said intermediate and lateral carrying means down from and up to a position to present said holders in position for receiving and leaving end plates of tube frames suspended on chains to and from position for presenting the yarn tubes of tube frames between warp threads, means for oscillating said holders on said carrying means and means for oscillating said pressing means on said holders.

15 2. In a mechanism for taking tube frames carrying spools of tuft yarn from carrying chains and presenting the yarn tubes of such tube frames between warp threads in a tufted pile fabric loom and after severance of the tuft yarn between the warp threads from that remaining on the spools, restoring the tube frames to the carrying chains, an intermediate arm intermediate between the sides of the loom and movable up and down, 25 an intermediate holder which is pivotally mounted on said intermediate arm and presenting a notch for receiving hook like projections extending in the general plane of end plates of tube frames is adapted to receive simultaneously two end plates of tube frames placed end to end in line, a pressing device in pivotal connection with said intermediate holder for pressing upon and releasing the tails of pivoted chain engaging hooks 30 of tube frame end plates in the notch of said holder and holding tube frame end plates therein, two lateral arms at the sides of the loom and movable up and down, two other holders which are pivotally mounted respectively on said lateral arms and presenting notches for receiving hook like projections extending in the general plane of end plates of tube frames are each adapted to receive one tube frame end plate at a time, pressing 35 devices respectively in pivotal connection with said other holders for pressing upon and releasing the tails of pivoted chain engaging hooks of tube frame end plates in the notches of said other holders and holding tube frame end plates therein, a shaft mounted to be oscillated for moving said intermediate and lateral arms down from and up to a position to present said holders in position for receiving and leaving end 40 plates of tube frames suspended on chains to and from position for presenting the yarn tubes of tube frames between warp threads, means for oscillating said holders on said arms and means for oscillating said pressing devices on said holders.

45 60

3. In a mechanism for taking tube frames carrying spools of tuft yarn from carrying chains and presenting the yarn tubes of such tube frames between warp threads in a tufted pile fabric loom and after severance

of the tuft yarn between the warp threads from that remaining on the spools, restoring the tube frames to the carrying chains, an intermediate arm intermediate between the sides of the loom and movable up and down, 70 an intermediate holder which is pivotally mounted on said intermediate arm and presenting a notch for receiving hook like projections extending in the general plane of end plates of tube frames is adapted to 75 receive simultaneously two end plates of tube frames placed end to end in line, a pressing arm in pivotal connection with said intermediate holder and presenting two 80 pressing parts for pressing upon and releasing the tails of pivoted chain engaging hooks of tube frame end plates in the notch of said holder and holding tube frame end plates therein, two lateral arms at the sides of the loom and movable up and down, two 85 other holders respectively which are pivotally mounted on said lateral arms and presenting notches for receiving hook like projections extending in the general plane of end plates of tube frames are each adapted 90 to receive one tube frame end plate at a time, pressing arms respectively in pivoted connection with said other holders and each presenting one pressing part for pressing upon and releasing the tails of pivoted chain 95 engaging hooks of tube frame end plates in the notches of said other holders and holding tube frame end plates therein, a shaft mounted to be oscillated for moving said intermediate and lateral arms down from 100 and up to a position to present said holders in position for receiving and leaving end plates of tube frames suspended on chains to and from position for presenting the yarn tubes of tube frames between warp threads, 105 means for oscillating said holders on said arms and means for oscillating said pressing arms on said holders.

4. In a mechanism for taking tube frames carrying spools of tuft yarn from carrying chains and presenting the yarn tubes of such tube frames between warp threads in a tufted pile fabric loom and after severance of the tuft yarn between the warp threads from that remaining on the spools, restoring the tube frames to the carrying chains, an intermediate arm intermediate between the sides of the loom and movable up and down, an intermediate holder which is pivotally mounted on said intermediate arm and presenting a notch for receiving hook-like projections extending in the general plane of end plates of tube frames is adapted to receive simultaneously two end plates of tube frames placed end to end in line, a pressing arm in pivotal connection with said intermediate holder and presenting two pressing parts for pressing upon and releasing the tails of pivoted chain engaging hooks of tube frame end plates in the notch 130

of said holder and having each pressing part adapted to press upon part of a tube frame end plate as well as upon the tail of a pivoted hook thereon and holding tube frame 5 end plates therein, two lateral arms at the sides of the loom and movable up and down, two other holders respectively which are pivotally mounted on said lateral arms and presenting notches for receiving hook-like 10 projections extending in the general plane of end plates of tube frames are each adapted to receive one tube frame end plate at a time, pressing arms respectively in pivoted connection with said other holders and 15 each presenting one pressing part for pressing upon and releasing the tails of pivoted chain engaging hooks of tube frame end plates in the notches of said other holders and holding tube frame end plates therein, a shaft mounted to be oscillated for moving said intermediate and lateral arms down from and up to a position to 20 present said holders in position for receiving and leaving end plates of tube frames suspended on chains to and from position for presenting the yarn tubes of tube frames between warp threads, means for oscillating 25 said holders on said arms and means for oscillating said pressing arms on said 30 holders.

5. In a mechanism for taking tube frames carrying spools of tuft yarn from carrying 35 chains and presenting the yarn tubes of such tube frames between warp threads in a tufted pile fabric loom and after severance of the tuft yarn between the warp threads from that remaining on the spools, 40 restoring the tube frames to the carrying chains, an intermediate arm intermediate between the sides of the loom and movable up and down, an intermediate holder which is pivotally mounted on said intermediate arm and presenting a notch for receiving hook-like 45 projections extending in the general plane of end plates of tube frames is adapted to receive simultaneously two end plates of tube frames placed end to end in line, a 50 pressing arm in pivotal connection with said intermediate holder and presenting two pressing parts for pressing upon and releasing the tails of pivoted chain engaging hooks of tube frame end plates in the notch of said holder 55 and holding tube frame end plates therein, two lateral arms at the sides of the loom and movable up and down, two other holders respectively which are pivotally mounted on said lateral arms and presenting notches for receiving hook-like 60 projections extending in the general plane of end plates of tube frames are each adapted to receive one tube frame end plate at a time and formed with a lateral oblique surface directed inwardly of the loom to receive contact of a tube frame end plate, pressing arms 65 respectively in pivoted connection with said other holders and each presenting one pressing part for pressing upon and releasing the tails of pivoted chain engaging hooks of tube frame end plates in the notches of said other holders and holding tube frame 70 end plates therein and each having its pressing part adapted to press upon part of a tube frame end plate as well as upon the tail of a pivoted hook thereon, a 75 shaft mounted to be oscillated for moving said intermediate and lateral arms down from and up to a position to 80 present said holders in position for receiving and leaving end plates of tube frames suspended on chains to and from position for presenting the yarn tubes of tube frames between warp threads, means for oscillating 85 said holders on said arms and means for oscillating said pressing arms on said 90 holders.

6. In a mechanism for taking tube frames carrying spools of tuft yarn from carrying 95 chains and presenting the yarn tubes of such tube frames between warp threads in a tufted pile fabric loom and after severance of the tuft yarn between the warp threads from that remaining on the spools, restoring the tube frames to the carrying chains, an intermediate arm intermediate between the sides of the loom and movable up and down, an intermediate holder which is pivotally mounted on said intermediate arm and presenting a notch for receiving hook-like 100 projections extending in the general plane of end plates of tube frames is adapted to receive simultaneously two end plates of tube frames placed end to end in line, a pressing arm in pivotal connection with said intermediate holder and presenting two pressing parts for pressing upon and releasing the tails of pivoted chain engaging hooks of tube frame end plates in the notch of said holder 105 and having each pressing part adapted to press upon part of a tube frame end plate as well as upon the tail of a pivoted hook thereon and holding tube frame end plates therein, two lateral arms at the sides of the loom and movable up and down, two other 110 holders respectively which are pivotally mounted on said lateral arms and presenting notches for receiving hook-like projections extending in the general plane of end plates of tube frames are each adapted to receive one tube frame end plate at a time and formed with a lateral oblique surface directed inwardly of the loom to receive contact of a tube frame end plate, pressing arms 115 respectively in pivoted connection with said other holders and each presenting one pressing part for pressing upon and releasing the tails of pivoted chain engaging hooks of tube frame end plates in the notches of said other holders and holding tube frame 120 end plates therein and each having its pressing part adapted to press upon part of a tube frame end plate as well as upon the tail of a pivoted hook thereon, a 125 shaft mounted to be oscillated for moving said intermediate and lateral arms down from and up to a position to 130 present said holders in position for receiving and leaving end plates of tube frames suspended on chains to and from position for presenting the yarn tubes of tube frames between warp threads, means for oscillating said holders on said arms and means for oscillating said pressing arms on said holders.

shaft mounted to be oscillated for moving said intermediate and lateral arms down from and up to a position to present said holders in position for receiving and leaving end plates of tube frames suspended on chains to and from position for presenting the yarn tubes of tube frames between warp threads,

means for oscillating said holders on said arms and means for oscillating said pressing arms on said holders.

In testimony that I claim the foregoing as my invention, I have signed my name this fifth day of May, 1925.

FRÉDERICK WILLIAM AUSTIN.
